UNITED STATES PATENT OFFICE.

JOSEPH H. WALSH, OF READING, MASSACHUSETTS, ASSIGNOR TO H. W. JOHNS-
MANVILLE COMPANY, A CORPORATION OF NEW YORK.

HEAT-PROTECTIVE COVERING.

1,332,314.

Specification of Letters Patent.

Patented Mar. 2, 1920.

Application filed January 13, 1919. Serial No. 270,834.

To all whom it may concern:

Be it known that I, JOSEPH H. WALSH, a citizen of the United States of America, residing at Reading, county of Middlesex, 5 State of Massachusetts, have invented certain new and useful Improvements in Heat-Protective Coverings, of which the following is a specification.

My invention relates to the heat conducting arrangement of structures which are to be subjected to very high temperatures and has an important application to the coverings of boiler blow-off pipes. These blow-off pipes must usually pass through the combustion chamber of the boiler furnace and are therefore constantly exposed to great heat. It has been customary to equip them with a covering of refractory and more or less non-conducting material, but it has been difficult to get any covering which will stand the continuous and intense heat and not fuse or crack off. If the covering is not a good conductor, none of the heat absorbed by the outer surface exposed to the flame and hot 25 gases is conducted away, and the covering is apt to gradually melt off. If it is a good conductor, the blow-off pipe is covered but not protected from heat action. I avoid the difficulty arising from these conflicting conditions by inserting, in the non-conducting covering, segments or elements of conducting material, such as cast iron which are so shaped as to make a good heat-transferring contact with the pipe, and project outward 30 to the exterior surface of the refractory covering. These conduct some of the heat from the covering to the blow-off pipe, which conducts it to the boiler, which is at the much lower temperature of the contained boiling water. Thus the temperature of the covering is maintained below its fusing point, while the pipe is protected from direct action of the flame and gases. Preferably these conducting elements are separable from the pipe so that if they become 35 badly burned or partly melted, they can be used for scrap and new ones substituted at little expense, the refractory covering being patched to suit requirements of the replacing operation.

The best form of apparatus embodying my invention at present known to me is illustrated in the accompanying two sheets of drawings in which,

55 Figure 1 is a vertical central section of a

portion of a steam boiler and its setting illustrating the blow-off pipe to which the invention is applied.

Fig. 2 is an enlarged side elevation and a partial section of said blow-off pipe and its 60 covering.

Fig. 3 is a cross section on line 3—3 of Fig. 2.

Fig. 4 is a cross section on line 4—4 of Fig. 2.

Fig. 5 is a detail side view on an enlarged scale of a modification, and

Fig. 6 is a cross section on line 6—6 of Fig. 5.

Throughout the drawings like reference 70 characters indicate like parts.

1, is the boiler, 2 the setting, and 3 the combustion chamber of the furnace formed under said boiler by the setting. 4, is the usual blow-off pipe which, as it connects to 75 the lowest point of the boiler, must extend through the combustion chamber of the furnace. 5, is the usual refractory and partially non-conducting covering for the pipe which preferably is formed as shown in Fig. 80 2, where 5^a is an asbestos rope wound about the pipe covered and embedded in a plastic mass 5^b, such as a mixture of short asbestos fiber with any suitable heat resisting cement, the whole being incased in a tubular covering 5^c. The parts may be held in position by a wire 12, wound around and through them.

To conduct a portion of the great heat absorbed by the exterior of this covering 90 away and so prevent the fusing point of the covering being reached, I employ elements of heat conducting materials such as cast iron having arc shaped portions 6, of a curvature such as will enable them to fit snugly 95 against the outer surface of the blow-off pipe, while from these arc-shaped portions extend radial portions 7, far enough to reach or pass beyond the surface of the refractory covering 5.

Various means for attaching these conducting elements to the pipe may be used. They may be perforated as shown at 9, and grooved, as shown at 10, to receive the fastening wire 11, by which one or more of the 105 elements may be fastened snugly against the pipe in the position shown in the drawing. Preferably the radial portions 7, are formed of two frusta of cones having their axes in line and their smaller ends 8, united. The 110

outer cone then forms a flaring head. This serves to retain the refractory covering in position should it crack and tend to fall off while the larger cross section of the inner cone as its base is approached affords a better conductivity for the heat. These conducting elements may be made with one radial projection each, as shown in Fig. 3, or with two or more as shown in Fig. 4. The latter form is especially useful for attachment to the pipe elbow, as shown in Fig. 2. Another, and very convenient form of means for fastening the conducting elements to the pipe is provided by shaping them with interlocking projections and recesses as shown in Figs. 5 and 6, where each element, as 16, has an inward projection 14, and recess 13, forming a hook at one end of the arc shaped section, and an outward recess 15, and projection 18, at the other end. When one such element, as 17, is slid over and under another, as 16,—as indicated in Fig. 6, and in dotted lines in Fig. 5,—the two elements interlock and are held in such interlocked position by reason of the pipe 4, filling up the interior of the circle formed by any two assembled arc shaped segments. By making the hooks formed by each set of adjacent projections and depressions, as 13—14, 15—18, point in the same direction—one toward the center of the arc, and the other outward—this interlocking action is obtained between elements which are duplicates each of every other, so that only one pattern is needed for casting, and the necessity of carrying in stock an even number of two different types,—which would be the case if the hooks pointed inward on one member and outward on the other,—is avoided.

The advantages of the invention are the preservative action of the conducting elements in mechanically holding the refractory covering in place and in reducing its temperature below the fusing point, the ease of application of the invention to any ordinary form of pipe, no special pipe casting being necessary, and the ease of replacement and repair if any one of the conducting elements becomes burned out.

Having described my invention, I claim:

1. A heat radiating and resisting structure comprising in combination a pipe adapted to conduct a relatively cool fluid, a covering for said pipe of refractory material in direct contact therewith and a

series of separate heat conducting elements adapted to be embedded in the refractory covering with portions projecting at the exterior surfaces of the refractory covering, while other portions of more extended area are adapted to rest against the pipe surface and transmit heat thereto from the outer portions of the refractory covering.

2. A heat radiating and resisting structure comprising in combination a pipe adapted to conduct a relatively cool fluid, a covering for said pipe of refractory material, indirect contact therewith and a series of separate heat conducting elements adapted to be embedded in the refractory covering with portions projecting at the exterior surface of the refractory covering, while other portions of more extended area are adapted to rest against the pipe surface and transmit heat thereto from the outer portions of the refractory covering, together with means for conveniently attaching said elements to, and detaching them from, the pipe.

3. A heat conducting element for use in preserving the refractory coverings for boiler blow-off pipes which consists of a mass of heat conducting material having a strip of small size relative to the mass of refractory covering shaped to an arc of a curvature corresponding to that of the exterior surface of the pipe to which it is to be applied, and a radially projecting portion, the ends of the arc shaped portion of said element being so shaped that they will interlock when a pair of such elements are assembled around the pipe.

4. A heat conducting element for use in preserving the refractory coverings for boiler blow-off pipes which consists of a mass of heat conducting material having a strip of small size relative to the mass of refractory covering shaped to an arc of a curvature corresponding to that of the exterior surfaces of the pipe to which it is to be applied, and a radially projecting portion, the arc shaped portion of said element being provided with similar hook-shaped portions, one pointing inward and the other outward to provide interlocking means when two elements are placed around the pipe in proper position.

JOSEPH H. WALSH.
